DESIGN FOR A SHAMPOO BOARD NECK REST

Elizabeth Wutzler, Alton, Ill.

Application October 29, 1936, Serial No. 65,573

Term of patent 3½ years

To all whom it may concern:

Be it known that I, Elizabeth Wutzler, a citizen of the United States and resident of Alton, in the county of Madison and State of Illinois, have invented a new, original, and ornamental Design for a Shampoo Board Neck Rest, of which the following is a specification, reference being had to the accompanying drawing, forming a part thereof.

Fig. 1 is a perspective view of a shampoo board neck rest embodying my new design.

Fig. 2 is a top plan view of the same;
Fig. 3 is a bottom plan view of the same;
Fig. 4 is an end view of the same.

I claim:

The ornamental design for a shampoo board neck rest, substantially as shown.

ELIZABETH WUTZLER.
